SNATCH BLOCK

William J. Lee, Lockport, N. Y., assignor to The Western Block Company, Lockport, N. Y., a corporation of New York

Application October 3, 1935, Serial No. 43,415

2 Claims. (Cl. 254—193)

The present invention relates to tackle blocks and has for its object to prevent the accidental disengagement of the releasable connection should the head be accidentally dropped while the block is coupled to the load.

The present invention is shown in the accompanying drawing in which—

Fig. 1 shows a perspective view of the block while in operation and coupled to the load;

Fig. 2 shows a similar view with the block open to receive the cable;

Fig. 3 shows a fragmental view somewhat enlarged as compared with Figs. 1 and 2, showing the parts in side elevation;

Fig. 4 shows a front elevation of the spring which prevents the accidental disengagement of the connection between the head and link;

Fig. 5 is a top plan view of the spring shown in Fig. 4.

Similar reference characters will be employed throughout the specification to designate corresponding parts.

In the drawing is shown a tackle block or, as it is sometimes called, a snatch block, excepting as will be pointed out, of well known construction comprising shell members 1 and 2 commonly made of wood, malleable iron, steel, or other material suitable for the purpose. To each of the shell members 1 and 2 are fixedly secured the suspension straps 3 and 4 held in place by any suitable means, as for instance the pockets 5 and 6, on the outer side which may be formed integrally with the shell members, and each of the suspension straps 3 and 4 bears against the upwardly extending supports 7 and 8 forming a part respectively of the shell members 1 and 2.

The block further comprises the usual head 9 which is pivotally engaged with the looped end of the strap 3 so that the head may swing from a disconnected to a connected position, as clearly shown in the drawing. The head 9 at a point diametrically opposite its connection with the loop of the strap 3 is provided with a horn or hook 10 arranged to be engaged by a loop or link 11 which is pivotally connected with the upper looped end of the strap 4. As usual in such constructions, the lower ends of the straps 3 and 4 project upwardly to a different extent so that when the head 9 is in the position shown in Figs. 1 and 3, the horn or hook 10 may be engaged with the loop or link 11, and when under load will remain in that position while the block is supporting the load, as for instance the cable passing over and around the pulley 12, or carried by the swiveled hook 13 carried by the head 9.

All the parts so far described may be of any usual or preferred construction and in and of themselves constitute no part of the present invention. Such blocks in use, when relieved of the load by the dropping of the head, frequently result in the accidental disconnection of the loop or link 11 with the horn 10 which if not discovered before lifting the load, frequently leads to serious accidents as in such a condition the weight or load will be entirely borne by the strap 3.

The object of the present invention is to prevent the accidental disconnection of the hook or horn 10 and loop or link 11, and for this purpose the block is provided with a spring 14 engaging the loop or link 11 at a point above its pivotal connection with the strap 4 so that, as indicated in dotted lines in Fig. 3, the spring has a tendency to always move the loop or link 11 from the position shown in dotted lines in that figure to the position shown in full lines, thus preventing the accidental disconnecting of the horn 10 with the loop or link 11.

The spring 14 is provided with a downwardly extending shank or tongue 15, an intermediate cross member 16, and the parallel upwardly extending arms 17 of such a length and so spaced with relation to each other than when in position, as shown in Figs. 1, 2, and 3, the arms 17 will bear upon the side members of the loop 11 exerting pressure thereon immediately above the pivotal connection of the lower end of the loop or link 11 with the strap 4, all as shown in Fig. 3 of the drawing. The spring 14 is secured in position by inserting the shank or tongue 15 in the socket 6, and when positioned as shown in Fig. 3, the pressure of the upwardly extending arms 17 against the link or loop 11 will hold the link 11 in operative position, ready to be engaged by the hook or horn 10 and to resist the accidental disconnection thereof.

The upper ends of the arms 17 of the spring 14 may be transversely dished or curved as shown at 18, forming upon their inner faces a concave seat 19 to more effectively engage the loop or link 11 which is generally made substantially round or circular in cross section. Obviously the spring 14 will be made of steel or other suitable spring material.

It is thought that the operation of my improved tackle or snatch block has been sufficiently described in connection with the foregoing description of its construction and that a further description of its operation will not be required.

I claim:

1. In a snatch block, in combination, shell members, open pockets on opposite sides thereof, a swinging head provided with a hook or horn, a support therefor mounted in one of the shell pockets, a loop or link arranged to engage the said horn, a support therefor mounted in the pocket on the opposite side, and a spring acting thereon, said spring having a shank fitted in said
- 5

latter pocket and extending upwardly therefrom in position to engage the loop or link.

2. A snatch block such as defined in claim 1, in which the shank of the spring is provided with a cross member extending laterally upon each 5 side thereof with upwardly extending parallel laterally spaced members arranged to engage the loop or link upon opposite sides of its support.

WILLIAM J. LEE.
